SCORE CARD HOLDER

Thomas King, Youngstown, Ohio

Application April 24, 1947, Serial No. 743,713

1 Claim. (Cl. 281—44)

1

This invention relates to score card holders and has to do more particularly with such score card holders as are intended to be carried in the pocket of the user. Cards to be used in tallying the results of various periods of sporting events are in quite popular use among many sportsmen, notably among marksmen and golfers, it being customary for one contestant to keep score for a team or foursome.

It is among the objects of the present invention to provide a compact, substantial score card holder which will keep the card in smooth, unwrinkled condition for repeated use.

It is a further object of the invention to provide, with a score card holder, an associated pencil holder to keep all of the scoring equipment ready at hand.

A still further object of the invention is the provision of a novel score card holder which is readily adaptable to selectively secure score cards of many different sizes.

Yet another object of the present invention is the provision of a novel article of manufacture amenable to fabrication from sheet metal, aluminum for example, and from wire, by simple stamping and bending operations.

With these and other objects in view attention is directed to the following detailed specification and description, wherein there is disclosed one illustrative embodiment of my invention, and to the accompanying drawing wherein:

Figure 1 is a plan view of the score card holder of the invention;

Figure 2 is a side elevation of the holder of Figure 1;

Figure 3 is an elevation of the lower end portion of the holder of Figure 1;

Figure 4 is a perspective view of the holder of Figure 1 showing the supported card and the secured pencil in their respective places; and,

Figure 5 is a plan view of the developed blank of a portion of the holder of Figure 1.

Referring now to the drawing more in detail, the reference character 10 indicates in general the main body of the card holder which is preferably fabricated of sheet aluminum and which may be stamped in the shape illustrated more clearly in Figure 5. A plurality of tabs (reference numerals 11 to 19 inclusive) may be formed at the time of stamping, which tabs serve the functions presently to be enumerated.

The tabs 11 and 17 are bent upwardly over the top surface of the body portion 10 (as viewed in Figure 1) and a uniform slot 17' is formed between the inner surface of tabs 11 and 17 and

the adjacent surface of body portion 10. Other tabs 12, 14 and 16 are bent downwardly in a direction opposite to that described in the case of tabs 11 and 17 and are turned to lie parallel with the under surface of body portion 10 as viewed in Figure 1. Thus a uniform slot 16' is formed between the inner surface of each of the tabs 12, 14 and 16 and the adjacent rear surface of the body portion 10. Slots 16' and 17' may be more readily viewed in Figure 2.

Tabs 13 and 15, which are initially longer than the tabs previously referred to are now curled loosely upon themselves in a direction toward the upper surface of the body portion 10 to form a pair of pencil-receiving eyes 15'. The portion of tabs 13 and 15 which lies closest to the surface of body portion 10 is spaced from the latter by a distance equal to the breadth of the slots 16' and 17'.

20 In this manner there are formed upon opposite upper and lower faces of body portion 10 discontinuous slots which are defined, in the case of the upper side, by the tabs 11 and 17 and by the outer surface of the pencil-receiving eyes 15' and 25 in the case of the lower side by the tabs 12, 14 and 16. A bent wire keeper, referred to generally by reference numeral 25, is placed against the left edge of body portion 10 and has its upper arm 26 positioned overlying the top surface of body portion 10 and its other arm 27 lying against the underside of body portion 10. The ends 26' and 27' of the arms 26 and 27, respectively, are slightly curved in a direction away from the adjacent surface of body portion 10 to facilitate use as 30 will be presently described. The center straight portion 28 is positioned parallel to the extreme left edge of body portion 10 where it is secured by the tabs 18 and 19 which are rolled to form eyes 18' and 19' respectively. As will be seen 35 in Figure 2 the eye 18' is disposed toward the upper surface of body portion 10 while the eye 19' is disposed toward the underside of the body portion 10.

I provide, upon the left edge of body portion 45 10, a pair of tapered projections 20 and 21 which at the points adjacent eyes 18' and 19' will be seen to project from the edge of body portion 10 a distance equal to the projection of eyes 18' and 19'. Thus it will be seen that projections 50 20 and 21 constitute fairing which serves to cover eyes 18' and 19', respectively, and to protect the clothing or person of a user from inadvertent danger upon the edges of said eyes.

In operation the device of the invention is utilized to secure a paper or pasteboard score card

55

30 and to hold it in readiness for the tallying of data. Score card 30 is attached to the holder by having its lower edge 30' inserted into slot 17' and its left-hand free edge 30'' slipped under the upper spring arm 26. This mode of attachment will serve in event that card 30 is no larger than body portion 10. In case the score card being used is substantially larger than the body portion 10, it may be folded at its centerline and wrapped about the right-hand edge of the holder while the edges of its upper and lower half will be inserted between the respective spring arms 26 and 27 and the respective adjacent faces of body portion 10. The lower edge, in this case, will be secured on the upper side within slot 17' and on the underside within slot 16'. Eyes 15' meanwhile hold in readiness a pencil 29.

There is thus provided a simple, compact, and readily useful assembly of holder, pencil and score card which accomplishes the objects initially set forth. The holder proper comprising the body portion 10 and the various tabs 11 through 17 inclusive afford a substantial surface upon which to write and securely hold an inserted score card with the aid of spring arms 26 and 27. Eyes 15' hold a writing implement in readiness and the entire assembly lends itself to easy insertion into the pocket of the user. The general contour of the holder with its suitably radiused corners and edges and its protecting projections 20 and 21 makes it pleasant and safe to handle.

Although I have illustrated and described the article of the invention as being constructed principally of sheet metal, preferably aluminum, it should be at once obvious that the principal body portion of the article may readily be produced at low cost by molding in plastics. When so produced the various tabs of the article such as the elements 11 through 17, 18' and 19' may be in the nature of separate metal members which are molded integral with the plastic sheet constituting the principal body member or which may be suitably attached to the body member after it is molded as will be understood.

At the upper end of the body member 10 I may

provide an aperture by which the score card holder of the invention may be readily supported by a string from a golf bag thereby further extending the range of usefulness of the article.

5 Also in the commercial production of the article I contemplate that suitable advertising material, as indicated at 32, may be incorporated directly in the principal body member of the holder and for this purpose the body member is made sufficiently long to extend slightly above the largest score card normally in use at the various golf courses in the land.

The above specifically described embodiments of the invention should be considered as illustrative only as obviously many changes may be made therein without departing from the spirit or scope of the invention. Reference should therefore be had to the appended claim in determining the scope of the invention.

20 What I claim is:

In a card-supporting device of a size suitable for carrying in a garment pocket, the combination of a flat plate-like base member, integral card-supporting tabs formed along one edge of said member and disposed to retain a card against both major surfaces of said base member, spring-retaining eyes formed along another edge of said base member and integral therewith, a U-shaped spring secured in said eyes and having its arms 30 overlying both major surfaces of said base member, and guard members formed on said another edge outwardly of said eyes.

THOMAS KING.
